EDWARD J. MORRIS, OF SYRACUSE, NEW YORK, ASSIGNOR OF ONE-HALF TO ANDREW J. L. PENDERGAST, OF SYRACUSE, NEW YORK.

CAN-HEADING MACHINE.

949,682.

Specification of Letters Patent. Patented Feb. 15, 1910.

Application filed May 15, 1909. Serial No. 496,202.

To all whom it may concern:

Be it known that I, EDWARD J. MORRIS, of Syracuse, in the county of Onondaga, in the State of New York, have invented new and useful Improvements in Can-Heading Machines, of which the following, taken in connection with the accompanying drawings, is a full, clear, and exact description.

This invention relates to certain improvements in can heading machines for crimping the marginal edges of the heads upon the ends of tin cans in such manner as to form an air tight joint and hermetically seal the cans without the use of solder at such joints.

The main body of the can is first made up in cylindrical form and its ends provided with outwardly projecting annular flanges, while the heads are of somewhat greater diameter than that of the end flanges on the cans, the central portions being slightly cup-shaped to fit into the end of the can, and the marginal edge is turned inwardly to form an annular flange surrounding that of the end of the can when the head is placed in position for crimping.

One of the objects of my invention is to provide a simple and more effective means for gradually but expeditiously crimping the marginal flange of the head over and upon that of the end of the can in such manner as to form a double fold or lap and at the same time to firmly press all parts of the flanges into close interlocking engagement with each other to make an absolutely air tight joint and thereby hermetically seal the can. This is accomplished through the medium of a non-rotatable axially movable presser head for engaging and holding the head of the can against turning, and a coaxial rotary axially movable head carrying suitable crimping rollers which are brought into engagement with the flange of the can head and then drawn inwardly toward each other under a rolling motion to overturn the marginal edge of the can head upon the end flange of the can; and another object of my invention is to provide means controlled by the operator whereby the rotary head may be rotated independently of the presser head and also independently of the mechanism by which it is moved axially.

One of the specific objects is to mount the crimping rollers in pairs upon separate rock

arms and to draw the rollers of one pair inwardly by the axial movement of the rotary head upon which said rock arms are mounted.

Another specific object is to cause one pair of rollers to be drawn inwardly slightly in advance of the other pair of rollers to partially crimp the edges of the can head while the second set of rollers complete the crimping operation.

Other objects and uses relating to specific parts of the machine will be brought out in the following description.

In the drawings:—Figure 1 is a vertical sectional view partly in elevation of a machine embodying the various features of my invention. Figs. 2 and 3 are enlarged horizontal sectional views taken respectively on lines 2—2 and 3—3, Fig. 1, showing particularly the revolving head, portions of said head being broken away in Fig. 3 to show the underlying crank arms. Fig. 4 is an enlarged elevation of the heads shown in Fig. 1 in operative position upon the head of a can, the lower portion of the non-rotatable head being shown in section. Fig. 5 is a vertical sectional view taken on line 5—5, Fig. 4, the shaft being shown in elevation. Figs. 6 and 7 are enlarged detail sectional views of one end of the can showing the can head uncrimped in Fig. 6 and crimped in Fig. 7.

The can, as —a—, is placed by hand or otherwise upon a suitable shelf or support —1— forming a part of the main supporting frame —2— of the machine, after which the head of the can, as —b—, is placed by hand or otherwise upon the upper open end of the can ready to be crimped thereon, the end of the cylindrical main body of the can being provided with an outwardly projecting annular flange —a'—, with which the marginal edge of the can head —b— is to be interlocked.

A rotary axially movable sleeve —3— is journaled intermediate its ends in a suitable bearing —4— on the main frame —2— and within this sleeve, and extending therethrough is a non-rotatable but axially movable spindle —5—, around which the sleeve —3— is adapted to rotate.

Slidably mounted upon the lower end of the sleeve —3— is a head —6— having a central lengthwise socket —7— opening from its under side and of greater diameter

than that of the sleeve forming an inner annular flange --8-- at the upper end of the head --6-- and fitting with an easy sliding fit upon the sleeve, the lower end of the socket being closed by a screw cap or hardened bearing plate --9-- having a central aperture through which the lower end of the spindle --5-- projects.

A collar --10-- is loosely fitted with an easy rotary fit upon the sleeve --3-- just above the head --6--, said head and collar being clamped together end to end by clamping screws --11-- which are passed through elongated slots --12-- in the flanges --8--, Figs. 3 and 5, and screwed into the under side of the collar --10--, the screws serving to hold the head --6-- and collar --10-- against relative endwise movement while the slots --12-- permit a limited rotary or rocking movement of the collar relatively to said head for a purpose hereinafter described. The upper end of the collar --10-- is provided with diametrically opposite slots or recesses --13-- open at the top and inclining downwardly and laterally in a direction opposite to the direction of rotation of the sleeve --3-- and heads --6-- for receiving radially projecting roller studs --14-- which are secured to diametrically opposite sides of the sleeve --3--, as best seen in Figs. 1, 4 and 5. The lower end of the sleeve --3-- within the socket --7-- is enlarged, forming an annular flange --15-- which fits with an easy sliding fit within the socket --7--, said head --6-- being locked to rotate with the sleeve --3-- by means of a key --16-- which enters a slotted key-way in the periphery of the flange --15--, as best seen in Fig. 5. The vertical length of the socket --7-- between the flange --8-- and bearing plate --9-- is somewhat greater than the vertical depth of the flange --15-- to permit a limited endwise movement of the head --6-- relatively to the sleeve --3-- which latter normally rests upon the flange --15-- when the sleeve --3--, spindle --5-- and head --6-- are in their extreme up position, as shown in Fig. 1.

Secured to the lower end of the spindle --5-- below the head --6-- and bearing plate --9-- is a presser head --17-- of slightly less diameter than the interior diameter of the can and having its lower face made to conform to the shape or contour of the central portion of the head --b-- of the can, the upper side of the head --17-- being provided with a ball race --18-- for receiving anti-friction ball bearings --19-- which bear against the under side of the bearing plate --9-- of the head --6-- when said heads are in their extreme up or down positions, said bearings --19-- serving to reduce the friction between the non-rotatable head --17-- and rotary head --6--.

The head --6-- is of considerably greater diameter than that of the can and carries

a plurality of upright rock shafts --20-- and --21-- which are spaced a uniform distance apart around the axis of the sleeve --3-- and spindle --5-- and some distance beyond the periphery of the head --17-- and also some distance beyond the extreme outer edges of the head --b-- of the can. These rock shafts --20-- and --21-- extend vertically through and beyond the lower and upper faces of the head --6--, the rock shafts --20-- being provided on their lower and upper ends respectively with oppositely projecting crank arms --22-- and --23--, while the rock shafts --21-- are also provided with similar oppositely projecting crank arms --24-- and --25--. The lower crank arms of the rock shafts project in the direction of rotation from their respective rock shafts, while the upper crank arms project in the opposite direction, all of said crank arms being arranged nearly tangential to a circle drawn through the axis of their respective rock shafts.

Mounted on the outer or advance ends of the lower set of crank arms --22-- are crimping rollers --26--, and upon the corresponding ends of the lower crank arms --24-- are mounted somewhat similar crimping rollers --27--, the set of rollers --26--, which operate first upon the marginal edges of the can head to partially crimp the same, being provided with annular grooves --28--, while the rollers --27-- (which may be termed the finishing rollers) are provided with similar but slightly flatter grooves --29--.

The upper set of crank arms --23-- are provided on their rear or trailing ends with rockable contact pieces --30-- adapted to be engaged by tangentially inclined cam faces --32-- on diametrically opposite sides of the collar --10--, said rocking contacts --30-- being pivoted to their respective crank arms --23-- and are allowed a limited movement against the action of suitable retracting springs --31-- for a purpose presently described. The rear or trailing ends of the upper crank arms --25-- are provided with laterally adjustable contact members --33-- which are slidably laterally and adapted to be adjusted by means of adjusting screws --34-- as best seen in Fig. 2. These contact members --30-- and --33-- project inwardly a short distance beyond the inner sides of their respective crank arms --23-- and --25--, the contact members --33-- being engaged by tangentially inclined bearings or cam faces --35-- which are also mounted on diametrically opposite sides of the collar --10--. The cam faces --32-- have a more abrupt incline and are somewhat shorter than the cam faces --35-- so as to cause the rollers --26-- to be operated a short period in advance of the operation of the rollers --27--. The precise operation

of these cams and crimping rollers will be more fully explained after the description of the driving mechanism.

Journalized in suitable bearings upon the main supporting frame is a horizontal driving shaft —36—, a main upright shaft —37— and a countershaft —38—, the driving shaft —36— being provided with a continuously rotating loose pulley —39— adapted to be connected to any available source of power not shown, and is also adapted to be connected to the shaft at the will of the operator through the medium of a clutch —40— which is operated by means of a hand lever —41— and connecting rod —42—, as best seen in Fig. 1.

Loosely mounted upon the lower end of the main shaft —37— is a rotary sleeve —43— which is connected to the driving shaft —36— by beveled gears —44— and is also connected to the countershaft —38— by gears —45—.

Secured to the upper end of the countershaft —38— is a gear —46— which transmits rotary motion to the sleeve —3— through the medium of idle gears —47— and a pinion —48—, the latter being keyed or feathered upon the sleeve —3—, as best shown in Fig. 1, so as to permit the sleeve to move endwise relatively to the pinion —48—. This pinion is provided with a hub —49— which is journaled in a suitable bearing in the main frame —2— and is held against upward displacement by a collar —50—.

Feathered upon the lower end of the main upright shaft —37— is a clutch collar —51— which is movable into and out of engagement with a clutch section —52— on the lower side of the adjacent gear —44— by means of a foot lever —53—, Fig. 1.

It is now clear that when the clutch —51— is thrown into engagement with the clutch section —52— rotary motion will be transmitted from the driving shaft —36— to the main shaft —37—, but when said clutch —51— is thrown out of engagement with said section —52— the main shaft —37— will be at rest, and at the same time rotary motion is imparted to the driving shaft —38— and thence through the mediums of the gears —46—, —47— and —48— to the sleeve —3—, which in turn rotates the head —6— and parts which are locked thereto. The axial movement of the sleeve —3— and spindle —5— is accomplished through the medium of grooved cams —54— and —55— and levers —56— and —57—, the cams —54— and —55— being secured to the upper portion of the main shaft —37— to rotate therewith and are only rotated when the clutch —51— is thrown into engagement with the clutch section —52—. The levers —56— and —57—

are pivoted respectively at —58— and —59— to portions of the main supporting frame at one and the same side of the shaft —37— and are provided with suitable studs or rollers which ride in their respective grooved cams —54— and —55—, the outer end of the lever —56— being provided with a similar stud which rides in a grooved collar —60— which is secured to the sleeve —3—. The outer end of the lever —57— is connected to a collar —60'— which is secured to the spindle —5—. It is now apparent that the sleeve —3— may be rotated without moving said sleeve or spindle —5— axially, or said sleeve and spindle may be moved axially during such rotation of the sleeve by means of the mechanism previously described.

The grooved cams —54— and —55— are so relatively formed and positioned as to cause the spindle —5— to move downwardly to force the presser head —17— against the head of the underlying can slightly in advance of the downward movement of the sleeve —3— and head —6— to assure the holding of the can head in proper position before the rollers —26— and —27— are brought into engagement with the marginal edges of the can head, whereupon the sleeve —3— is depressed by the action of the cam —54— allowing the head —6— to follow downwardly by gravity until the bearing —9— engages the roller bearings —19— in which position the rollers —26— and —27— are disposed in substantially the same plane 100 but some distance from the marginal edges of the head of the can, and by continued downward movement of the sleeve —3— relatively to the head —6— (which movement is permitted by the elongated socket —7—) the roller studs —14— are depressed against the inclined sides of the slots —13— thereby rotating the collar —10— and cams —32— and —35— thereon against their respective contact members —30— and —33—, thereby rocking the corresponding upper crank arms —23— and —25— outwardly against the action of suitable retracting springs —23'— and —25'— and effecting a corresponding inward rocking movement of 115 the lower crank arms —22— and —24— which moves the rollers —26— and —27— into contact with the marginal edges of the head —6— of the can. It is evident, however, that the rollers —26— will be first to engage and partially crimp the marginal edges of the head of the can by reason of the steeper incline of the cams —32— and that these cams —32— will be moved beyond the contact points of the corresponding members —30— before the cams —35— complete their operation upon the crank arms —25—, thereby allowing the contact members —30— to drop behind the cams —32— and thus permitting the rollers —26— to be 120 125 130

rocked away from the marginal edges of the head of the can after performing their work. The cams —35—, however, which are longer than the cams —32— continue to further act upon the arms —25— to press the rollers —27— inwardly and additionally crimp the edges of the head of the can to give the desired finish and hermetically seal the joint, this operation being accomplished during substantially half a revolution of the main shaft —37—, the remaining part of such revolution serving to draw the sleeve —3— and spindle —5— to their normal up positions, the sleeve —3— being moved upwardly first and causes the rollers —14— to ride upwardly in the inclined slots —13— for restoring the rollers to their normal out positions. During the upward movement of the sleeve —3— relatively to the head —6—, the contact members —30— are forced backwardly against the action of the springs —31— by and out of the path of the cams —32— to permit the collar —10— to resume its normal position, said contact members —30— also assuming a normal starting position. The members —30— and —33— are normally held in contact with their respective cams —32— and —35—. As previously stated the cams —32— are considerably shorter and steeper tangentially than the cams —35—, so as to cause the corresponding rollers —26— to engage and partially crimp the marginal edges of the cap of the can in advance of the finishing operation by the rollers —27—. That is while the head is rotating, the free ends of the pawls —30— ride up the inclines and drop in behind the cams —32— and effect the corresponding movement of the rollers —26— to partially overturn the edges —b— of the cap under the flanges —a— of the can which action is immediately followed up by the action of the cams on the arms —25— to finish the crimping operation, the cams —35— having a slight yielding movement under the action of suitable springs —35'—. The upward return movement of the sleeve —3— and spindle —5— to their normal positions operates the return of the cams —32— and —35— to their starting positions, the spring —31— permitting the pawl —30— to trail over the point of the cam —32— and to assume its normal bearing upon the face of said cam.

The operation of my invention will now be readily understood upon reference to the foregoing description and accompanying drawings, and it will be observed that the two important features I wish to protect are first, the means for moving the crimping rollers inwardly and outwardly toward and away from the head of the can, and also means for connecting and disconnecting the driving mechanism from the main shaft —37— which controls the reciprocal movement of the spindle —5— and head —6—.

What I claim is—

1. In a can heading machine, a rotary axially movable sleeve, a collar loose upon the sleeve, coacting means on the collar and sleeve for rotating the collar on the sleeve as the sleeve is moved axially, a head rotated by the sleeve, rock arms on the head, coacting devices between the collar and rock arms for rocking said arms as the sleeve is moved axially, and crimping rollers on the rock arms.

2. In a can heading machine, a rotary axially movable sleeve, a spindle passed through said sleeve, a press head on the lower end of the spindle, an additional head co-axial with and rotated by said sleeve, a collar loosely mounted on the sleeve, coacting devices between the sleeve and collar for partially rotating said collar on the sleeve as the latter is moved axially, rock arms on said additional head, crimping rollers on the rock arms and co-acting devices between the collar and rock arms for rocking the latter as the collar is rotated by the axial movement of the sleeve.

3. In a can heading machine, a rotary axially movable sleeve, a collar loose on the sleeve, a head co-axial with and rotated by said sleeve, diametrically opposite rock arms on the head, crimping rollers on the rock arms, co-acting devices between the sleeve and collar for rotating said collar relatively to the sleeve as the sleeve is moved endwise, cams on the collar, and means actuated by said cams for rocking said arms as the collar is rotated by the axial movement of the sleeve.

4. In a can heading machine, a rotary axially movable sleeve a head coacting with and rotated by the sleeve, a collar loose on the sleeve and provided with inclined elongated slots, radial studs on the sleeve riding in said slots to rotate the collar relatively to the sleeve as the sleeve is moved endwise, cams projecting from the periphery of the collar, rock shafts journaled on the head, rock arms contacting with said cams and secured to said rock shafts, lower rock arms secured to said shafts, and crimping rollers on the lower rock arms.

5. In a can heading machine, an upright main shaft, a sleeve rotatable on the shaft, means for rotating said sleeve, an upright counter shaft, means for transmitting rotary motion from sleeve to counter shaft, a rotary axially movable sleeve, means for transmitting motion from the counter shaft to the last named sleeve independently of the main shaft, means for connecting and disconnecting the main shaft to the first named rotary sleeve, means actuated by the main shaft for moving the second sleeve endwise, a head co-axial with and rotated by said second sleeve, rock arms carried by the head, crimping rollers mounted on the rock arms,

and mechanism actuated by the axial movement of the second sleeve for rocking said arms.

6. In a can heading machine, a main upright shaft, a sleeve loose upon the shaft, means for rotating said sleeve, a clutch for connecting and disconnecting the main shaft to the sleeve, a counter shaft, means for transmitting motion from the sleeve to the counter shaft, a second sleeve rotatable and movable axially, means for transmitting rotary motion from counter shaft to the second sleeve, a non-rotatable spindle passed through the second sleeve and movable axially thereof, a press head on the lower end of the spindle, a crimping head on the lower

end of the second named sleeve, crimping rollers on said crimping head, means actuated by the axial movement of the second sleeve for moving said rollers toward and from the axis of the crimping head, means actuated by the main shaft for moving the sleeve axially, and additional means on said main shaft for moving the spindle and press head axially. 20

In witness whereof I have hereunto set my hand this 8th day of May 1909.

EDWARD J. MORRIS.
